UNITED STATES PATENT OFFICE

170,268

AIRPLANE

Joseph F. Liebhaber, Merrimac, Wis.

Application November 28, 1952, Serial No. 22,478

Term of patent 14 years

(Cl. D71—1)

To all whom it may concern:

Be it known that I, Joseph F. Liebhaber, a citizen of the United States, residing at Merrimac, county of Sauk, and State of Wisconsin, have invented a new, original, and ornamental Design for an Airplane, of which the following is a specification, reference being had to the accompanying drawings, forming a part hereof.

Figure 1 is a top plan view of an airplane, showing my new design;

Figure 2 is a side elevational view;

Figure 3 is a rear end view;

Figure 4 is a longitudinal sectional view taken on the line 4—4 of Figure 1;

Figure 5 is a front elevational view; and
Figure 6 is a transverse sectional view taken on the line 6—6 of Figure 2.

I claim:

The ornamental design for an airplane, as shown.

JOSEPH F. LIEBHABER.
